UNITED STATES PATENT OFFICE.

THEODORE N. VAIL, OF BOSTON, MASSACHUSETTS, AND JOHN A. SEELY, OF NEW YORK, N. Y.

TELEPHONE-CENTRAL-STATION APPARATUS.

SPECIFICATION forming part of Letters Patent No. 394,230, dated December 11, 1888.

Application filed August 31, 1888. Serial No. 284,238. (No model.)

To all whom it may concern:

Be it known that we, THEODORE N. VAIL, of Boston, county of Suffolk, and State of Massachusetts, and JOHN A. SEELY, of the city, 5 county, and State of New York, have jointly invented certain new and useful Improvements in Telephone-Central-Station Apparatus, of which the following is a specification.

10 Our invention relates to the construction and arrangement of telephone-central-station switch-boards, and is an improvement upon the arrangement of apparatus shown, described, and claimed in our Letters Patent dated July 10, 1888, numbered 385,974 and 15 385,976.

One feature of improvement consists in a novel arrangement of apparatus for connecting the circuits assigned to the care of 20 one operator (called by us a "group") with a head telephone, whereby calls may be received without preliminary signaling.

We provide the local circuit containing the head telephone with a series of spring-jacks. 25 The subscribers' circuits terminate in spring-jack plugs, as described in said patents, and the number of spring-jacks in the local circuit is equal to the number of circuits in a group—that is, in the head telephone local 30 circuit there is a spring-jack for every subscriber's circuit in the group, and the jack-plug forming the terminal of every such circuit is normally located in one of these spring-jacks. We prefer to connect the spring-jacks in multiple arc with the head telephone. We 35 have also improved the construction and arrangement of keys or push-buttons for ringing in either of two directions upon a metallic circuit and for "looping in" a listening-telephone, with respect to a pair of connected metallic circuits, during the process of conversation between the terminal stations. This 40 operation of looping in has heretofore been practiced by breaking the circuit and inserting a listening-telephone; but the operation of breaking the circuit frequently produces an interruption, and in circuits the use of which is frequently called for the operation

becomes a very serious cause of interruption.

Our improvement consists in connecting the 50 terminals of a local circuit containing a listening-telephone to opposite sides of a pair of united metallic circuits. This produces no preliminary break and no interruption or variation whatever.

55 The accompanying drawings illustrate our invention.

Figure 1 is a side view of the apparatus, showing details of the calling and looping-in keys. Fig. 2 is a plan view of the arrangement 60 of the head telephone and group circuits connected in parallel by means of a series of spring-jacks in a local circuit.

G' and G² represent two separate switch-boards upon a multiple-board system or arrangement. The metallic circuit c c' passes through a jack, j', on board G', through jack j² on board G², thence through three push-buttons, C C' C², to be described, and terminates in a spring-jack plug, P, adapted to operate in connection with any of the spring-jacks j' j².

70 T is an operator's head telephone permanently connected into a local circuit, 19 20.

J is a spring-jack adapted to receive a 75 jack-plug like P. There are a series of circuits like c c'—say to the number of one or two thousand, or more. Of these there are, say, one hundred assigned to the special care 80 of an operator at board G², as more fully described in our Letters Patent before referred to. Every circuit of this group of one hundred of course terminates in a plug, P, and there are one hundred spring-jacks, J, connected with the local circuit 19 20. Each plug P is 85 normally located in one of these jacks J. The result is that every circuit of the group of one hundred is normally connected with the head telephone T, and no preliminary signaling is required to get the attention of the central-station operator. We prefer to connect the 90 series of jacks J in multiple arc, so that when a plug P is withdrawn the local circuit is not left open. The special form of spring-jack used by us is normally open to avoid 95 short-circuiting the telephone, and is only

closed by the insertion of a jack-plug; but if it be preferred to connect these jacks in series they must be so constructed as to close the circuit when the plug is withdrawn. The 5 operation beyond this point is well known, but is fully described in our heretofore-mentioned patents.

For the purpose of ringing in either direction and "listening in," we have provided 10 three keys or push-buttons, C C' C². They are of similar construction, and are fixed into the frame F of the board. Each key consists of two strips, s s', which, together with the contacts 1 and 2 in electrical connection 15 therewith, are firmly fixed to opposite sides of a block of insulating material, d, which is perforated to form a bearing for the rod r, having a button upon its upper end and a wedge-shaped section of insulating material, 20 i, upon its opposite end, acting to force apart the spring-contacts 1 and 2. Near the end of strips s s' is a block of insulating material, f, located in which, at substantially equal intervals, are two pairs or four conducting-contacts, 3 4 5 6. The contacts 1 and 25 2 are located in position to make contact with one pair of such contacts, respectively—that is, contact 1 is in position to electrically unite with either contact 3 or 5, and contact 2 is in position to electrically unite with either contact 4 or 6. In both cases the position of 1 and 2, as regards the two pairs of contacts 3 and 5, 4 and 6, is controlled by the position of the wedge-shaped section of insulating material, i.

The keys C and C' are for ringing in either of two directions upon connected metallic circuits. C rings in one direction; C' rings in the other direction. A source of electricity, b, is 40 connected to the contacts 5 and 6 of each key. The line-circuit c c' normally passes through the contacts 1 and 3, 2 and 4. The rod r being depressed, spreads the contacts 1 and 2 to maintain this connection; but when i is withdrawn the source of electricity b of C is connected into the circuit entering from one direction. Regarding C' when i is withdrawn, the source of electricity b is connected into the circuit entering from the opposite direction. The drawings show the apparatus in a 45 normal position. If C be operated, circuit will be via c', s, 1, 5, b, 6, 2, s', c. If C' be operated, the circuit c c' will be left open, and the circuit entering by flexible cord m will 50 pass through C' via elements s', 2, 6, b, 5, 1, s, and out via m, it being assumed that P and m have been connected with a called-for circuit.

The key C² is used to loop the telephone-set L 1 into connected circuits. The contacts 3 and 4 for this purpose are dead and useless, and a key with four contacts instead of 65 six is all that is required; but for the purpose of preserving uniformity and interchangeability the same construction of key has been

used. The telephone-set L 1 is in local circuit 90 91, connected to the terminals 5 and 6 of key C², the strip s is connected to c', and the strip s' is connected to c. Upon operating c² the circuit 90 91 is connected to opposite 70 sides of the metallic circuit, and it is therefore in parallel circuit with the telephone-sets at opposite terminals of the connected metallic circuits, and the conversation passing between the terminal stations is audible 75 to the central-station operator, but no interruption occurs.

What we claim, and desire to secure by Letters Patent, is—

1. The combination of a central station, a 80 series of sub-stations, a series of electrical circuits, one for each sub-station, a telephone-instrument for each circuit at the sub-station, a telephone in a local circuit at the central station, a series of normally-open spring-jacks in said circuit connected in parallel, 85 and a series of jack-plugs, one for each sub-station circuit, for connecting and disconnecting each sub-station circuit with said local circuit in parallel circuit, substantially as described.

2. The combination, at a telephone central station, of an electrical circuit and a key or push-button for ringing or signaling a sub-station, consisting of a pair of fixed contacts, 95 a pair of movable contacts, an insulating-wedge normally located between and forcing the movable contacts into connection with said fixed contacts to complete the circuit, and a second pair of fixed contacts forming 100 the terminals of a source of electricity located in position to connect with said movable contacts when the wedge is withdrawn, whereby the source of electricity is inserted to ring or signal, substantially as described.

3. The combination of a central station and a series of sub-stations, a series of metallic circuits, one for each sub-station, means for connecting said circuits in pairs at the central station, and a pair of keys or push-buttons for inserting a source of electricity with respect to one of such pair of circuits, respectively, each key consisting of a pair of fixed contacts, a pair of movable contacts, and an insulating-wedge located on a movable support normally between and in position to force said contacts into connection with the pair of fixed contacts to complete the circuit, and a second pair of fixed contacts forming the terminals of a source of 110 electricity located in position to connect with said movable contacts when the wedge is withdrawn, whereby the source of electricity 115 is inserted, substantially as described.

4. The combination of a central station, a 125 series of sub-stations, a series of metallic circuits, one for each sub-station, means for connecting circuits in pairs, a telephonic instrument at each sub-station, a telephone in a local circuit at the central station, a series of 130

switches, one for each circuit, located at the central station, each switch consisting of a pair of contacts connected to the terminals of the local circuit, a pair of contacts connected to points on opposite sides of the metallic circuit, one of said pairs of contacts being located between the other pair, and a wedge of insulating material normally separating one

pair of contacts, located upon a rod having a reciprocating movement, substantially as described.

THEO. N. VAIL.
JOHN A. SEELY.
